CLAIM

The ornamental design for a circuit analyzer, as shown and described.

DESCRIPTION

FIG. 1 is a front, top, right perspective view of a circuit analyzer according to the invention;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevational view thereof, the right side elevational view being a mirror image; and,

FIG. 7 is a top, rear, left perspective view thereof.

The broken lines shown represent unclaimed subject matter and form no part of the claimed design.
